(57) **CLAIM**

The ornamental design for a compact fluorescent lamp, as
shown.

DESCRIPTION

FIG. 1 is an elevational view of a compact fluorescent lamp
showing our new design, the front, rear, and side elevational
views being identical;

FIG. 2 is a top plan view thereof; and,

FIG. 3 is a bottom plan view thereof.

The disclosed lamp is formed in an ornamental shape which
makes a compact fluorescent light bulb attractive for use in
sconces and chandeliers.
